WALTER H. KNISKERN, OF SYRACUSE, NEW YORK, ASSIGNOR TO ATMOSPHERIC NITROGEN CORPORATION, OF SOLVAY, NEW YORK, A CORPORATION OF NEW YORK.

MEANS FOR UTILIZING THE ENERGY OF LIQUIDS UNDER PRESSURE CONTAINING GASES.

Application filed December 17, 1923. Serial No. 681,149.

This invention relates to means for utilizing the energy contained in liquids under pressure which hold gases, chiefly in solution. It is well known that, generally speaking, liquids will absorb or dissolve greater amounts of gases if the pressure is increased. The utilization of a current or jet of liquid discharged under pressure, for the operation of turbines or other machinery, is also quite common. I have found, however, that when the liquid thus discharged contains gases, the latter, as they are released from the liquid owing to the reduction of pressure, will tend to scatter or break up the liquid so that it will no longer form a substantially solid jet suitable for the efficient operation of a water wheel or the like, but will be diffused as a spray having but little driving power. The object of this invention is to obtain a practically efficient jet even when the liquid contains gases which, with the constructions employed hitherto, would cause the liquid to assume the form of an inefficient spray upon its release from the conduit through which such liquid is discharged.

The present improvement is of special utility in connection with the utilization of energy of liquid under pressure discharged from certain washing apparatus or scrubbers forming part of a synthetic ammonia plant, the general type described, for example, in the application of F. W. de Jahn, Serial No. 200,047, filed November 3, 1917, and the present invention will consequently be described with reference to such a plant.

This type of plant involves in one of the details of procedure the passing of a gas mixture containing nitrogen and hydrogen (and associated impurities such as CO₂, CO, etc.) under a pressure of approximately 95 atmospheres through a water scrubber through which water is continuously forced by a pump. A pressure of about 95 atmospheres prevails in such a scrubber and it has been proposed to utilize the water or liquor discharged from this scrubber by projecting it from a nozzle as a stream or jet against the buckets of a device such as a Pelton water wheel. It was found, however, that the water from the scrubber containing as it does a relatively large amount of dissolved gas, chiefly carbon dioxide, developed a tendency to spread and scatter the water as soon as it emerged from its nozzle and that only a low

efficiency result was obtainable from the water wheel thus operated.

The nozzle which is the subject of the present invention is designed to overcome the difficulties hitherto experienced and to supply an efficient means of securing an effective jet even though the water contains a large amount of dissolved gas.

A specific example of my invention will now be described in detail with reference to the accompanying drawings, in which Fig. 1 is a diagrammatic view of that portion of an ammonia plant for which my invention is primarily intended; and Fig. 2 is a longitudinal vertical section through the improved nozzle and adjacent parts.

At 10 I have indicated a motor (generally an induction electric motor) on the shaft 11 which drives the pump 15. The pump 15 takes in water through a suitable inlet and forces such water at a pressure of about 95 atmospheres through a delivery pipe 16 into a water scrubber 17, from the outlet of which the water, together with the gases it has absorbed or dissolved, passes through a pipe 18 to the improved nozzle, designated as A in Fig. 1, and shown in detail in Fig. 2. The jet issuing from this nozzle is projected against a fluid motor, for instance a Pelton water wheel 19 mounted on the shaft 11. The energy in the liquid discharged through the nozzle A, is thus utilized to rotate the shaft 11 in the same direction that it is driven by the motor 10, and thus a motor of relatively small power will suffice for the operation of the pump.

The gases (chiefly carbon dioxide) which the liquid takes up under the heavy pressure (about 95 atmospheres) maintained in the scrubber 17, escape in large part from such liquid as the pressure is relieved, and in thus expanding and separating themselves from the liquid, the gases will break the liquid into a spray if the nozzle is of the construction customarily employed for Pelton wheels operated by water containing no gas. In this usual construction, the nozzle channel or bore is of short length and circular at the outlet. In my improved construction, the nozzle channel expands or flares toward the outlet, and by this arrangement, I not only avoid the scattering or spraying effect which the liberation of gas tends to produce in the liquid jet with consequent loss of

power, but I utilize, as a motive power, energy of the previously compressed dissolved gas as well as energy of the water.

In Fig. 2, the nozzle body is indicated at 20, said body having a passage contracted toward the outlet, in the usual manner. A separate nozzle portion 21 is fitted against the front end of the body 20, and with the outlet of said portion co-operates the needle 22, adjustable lengthwise, either by means of the customary handwheel, or through any well-known automatic mechanism such as indicated diagrammatically at 12 as controlled from the float valve mechanism 3 of the float chamber 14, so that the nozzle opening will be varied automatically in accordance with the amount of water to be removed from the scrubber 17. The front end 23 of the nozzle portion 21 projects into a corresponding recess provided in a flange 24 located at the rear end of the nozzle tip 25. The latter in the specific embodiment shown has a longitudinal passage 26 which widens gradually toward the discharge end, the cross-section 25 of said passage, at its inner or receiving end, being the same as the cross-section of the passage of the nozzle portion 21, at the discharge end of such portion. The passage 26 may be given other configurations, but its exit orifice should always be larger than the space through which the fluid leaves the nozzles between the nozzle portion 21 and the forward end of the needle 22. The outlet end of the nozzle tip 25 is cut off obliquely, as indicated at 25', thereby minimizing the free space between the exit orifice of the nozzle and the blades or buckets of the water wheel 19. If the size of the nozzle opening is properly designed there will be no appreciable tendency of the jet to diverge and the oblique extension 25' will not be necessary.

The parts 20, 21 and 25 may be an integral structure but, as shown, are held together by means of a nut 27 screwed on the nozzle body 20 and having a flange 28 to engage the flange 24, and a shoulder 29 opposed to a flange at the inner end of the nozzle portion 21. If desired, suitable packings (not shown) may be placed at the joints between the parts 20, 21, 25 and 27.

As the mixture of liquid and gas passes beyond the needle valve 22, the pressure upon the liquid is released and the dissolved gas is set free. As this gas expands, its energy is transferred to the liquid flowing through the nozzle tip channel 26 and thus the velocity of the fluid flowing through said channel is increased. The size of the outlet of the nozzle tip is made such that the pressure at that point will be substantially the same as that existing within the casing of the Pelton wheel. When the mixture of water and gas leaves the nozzle tip it is therefore under practically no extra pressure, that is to say, there is no tendency

for more gas to escape from the water or for the gas already evolved to expand further. Thus, instead of a scattering spray I obtain a substantially uniform and cylindrical solid jet of gas and water, the particles of which flow in substantially parallel paths. Such a solid jet is highly efficient for the operation of a Pelton water wheel or other motor actuated by a liquid jet. The new arrangement is also very efficient in that the energy derived from the expansion of the dissolved gas is converted into energy of motion imparted to the mixture of water and gas.

While it is desirable to have the opening at the outlet of the nozzle tip 25 of such size as referred to above, that the gas will have expanded fully by the time it reaches said outlet, yet results better than those obtainable with the usual construction will be secured even if said outlet opening is smaller, as long as such outlet opening is substantially larger than the cross-sectional area of the free space between the needle 22 and its seat 21.

On the other hand, in order to secure the best results, the forward opening of the tip 25 should not be made too large but should be so dimensioned that as nearly as possible the pressure at that point approximates that prevailing in the Pelton wheel casing. Since the movement of the needle 22 renders it impossible to obtain permanency of conditions in this respect the best practice is to design the size of the wide-end opening of 25 according to the average flow through the nozzle 21.

It is desirable to make the nozzle 21 and needle 22 of tool steel or bronze so that it may withstand the chemical action of carbon dioxide and the chemical or mechanical action of other substances that may be contained in the liquid coming from the scrubber 17.

The invention, although described with reference to a pressure system of 95 atmospheres, may obviously be employed where the pressure is either greater or less and various other changes may obviously be made in the details of construction without departing from the scope of this invention.

I claim:

1. In combination, means for operating a gas scrubber under high pressure to cause a gas not readily soluble in the scrubbing liquid at ordinary pressures, to be absorbed in said liquid, and means for recovering potential energy residing in the gas charged exit liquid from the scrubber, said last named means comprising a channel for said exit liquid, a nozzle connected to said channel, said nozzle being shaped to permit the escape within the confines of the nozzle of a portion of the dissolved gas from the liquid without scattering the solid jet of liquid to any substantial degree, and a fluid motor

operated by the jet of liquid issuing from said nozzle.

2. In combination, means for operating a gas scrubber under high pressure to cause a gas not readily soluble in the scrubbing liquid at ordinary pressures to be absorbed in said liquid, and means for recovering potential energy residing in the gas charged liquid product of said scrubber, said last named

10 means comprising a channel for said liquid, a nozzle connected to said channel, said nozzle first contracting from the size of said channel to a small throat and then gradually expanding to form a substantially long nozzle tip having an outlet area substantially larger than that of said throat whereby the solidity of the liquid stream is preserved while gas is liberated from said stream within the nozzle, and a fluid motor operated by 20 the solid stream of liquid issuing from said nozzle tip.

3. In the art of high pressure gas scrubbing wherein a liquid becomes charged with a gas which at ordinary pressures is not readily soluble in said liquid, that improvement which consists in recovery of potential energy residing in the exhaust scrubbing liquid charged with the gas by reason of the high pressure of the scrubbing operation, 30 by conducting the said liquid through a nozzle to a space of lower pressure and in the nozzle gradually releasing some of the gas contained in said liquid to preserve the solidity of the stream of said liquid as it issues from said nozzle, and finally discharging the said stream of liquid in a fluid motor to cause the operation thereof.

4. In combination with a gas scrubber for causing absorption in a liquid under high pressure, of a gas which is not readily soluble in such liquid at ordinary pressures, means for delivering gas under high pressure to the scrubber, means for delivering the liquid scrubbing agent to the scrubber 45 inlet, a nozzle receiving gas-charged pressure liquid from said scrubber and having a

channel expanding toward the nozzle outlet, a motor operated by the jet issuing from said nozzle, a device for varying the flow through said nozzle, and a connection operative upon said device and sensitive to variations in the amount of liquid to be removed from the scrubber to vary the flow through the nozzle in accordance with such variations.

5. In the art of high pressure gas scrubbing, wherein a liquid becomes charged with a gas which at ordinary pressures is not readily soluble in said liquid, that improvement which consists in the recovery of potential energy residing in the exhaust scrubbing liquid charged with the gas by reason of the high pressure of the scrubbing operation, by conducting the said liquid through a nozzle to a space of lower pressure and in 65 said nozzle gradually releasing some of the gas contained in said liquid to preserve the solidity of the stream of said liquid as it issues from said nozzle and finally discharging the said stream of liquid in a fluid motor 70 to cause the operation thereof, all of the aforesaid operations being conducted under substantially constant temperature conditions.

6. In combination with a gas scrubber for 75 causing absorption in a liquid, under high pressure, of a gas which is not readily soluble in such liquid at ordinary pressures, means for delivering gas under high pressure to the scrubber, means for delivering 80 the liquid scrubbing agent to the scrubber, a nozzle for receiving gas-charged pressure liquid from said scrubber and having a channel expanding toward the nozzle outlet, a motor operated by the jet issuing from 85 said nozzle, and means for transmitting the resultant power of said motor to the means which cause delivery of the liquid scrubbing agent to the scrubber.

In testimony whereof I have hereunto set 90 my hand.

WALTER H. KNISKERN.
